United States Patent Office.

MATTHEW QUINN, OF WATAGA, ILLINOIS.

Letters Patent No. 96,146, dated October 26, 1869.

IMPROVED RAILWAY-CAR COUPLING.

The Schedule referred to in these Letters Patent and making part of the same.

To all whom it may concern:

Be it known that I, MATTHEW QUINN, of Wataga, in the county of Knox, and State of Illinois, have invented a new and useful Improvement in Car-Coupling; and I do hereby declare that the following is a full, clear, and exact description thereof, which will enable others skilled in the art to make and use the same, reference being had to the accompanying drawings, forming part of this specification.

Figure 1 is a vertical longitudinal section of my improved coupling, taken through the line $x x$, fig. 2.

Figure 2 is a front view of the same.

Figure 3 is a side view of the same.

My invention has for its object to furnish an improved self-coupling car-coupling, designed more especially for freight-cars, but equally applicable to other cars, and which shall be so constructed and arranged as to conveniently couple cars differing in height; and

It consists in the construction and combination of various parts of the coupling, as hereinafter more fully described.

A is the bumper-head, which is made with two mouths placed the one directly above the other, and each being made hopper-shaped, so that when the cars are run together, the coupling-link may enter one or the other of said mouths, according to the height of the other car.

The two-mouthed bumper-head A may be made in one piece, or the upper mouth may be made in a separate piece, and securely attached to the lower part.

The latter construction is used when it is desired to attach my improvement to old bumpers, but in making new bumper-heads the former construction is preferred.

The lower incline a of the lower mouth of the bumper-head is made detachable, and is secured in place by a bolt, or bolts, as shown in figs. 1 and 2, so that the said incline may be removed to allow the bolt to be inserted, by means of which the bumper-head is connected to the car.

The upper sides of both mouths are slotted to receive the coupling-pins or catches B, one of which is used in each mouth.

The pins or catches B are formed with gudgeons on each side, which enter and work in recesses prepared to receive them in the bumper-head.

The pins or catches B are pivoted and secured in

place by pins passing horizontally through the sides of the bumper-head and through the gudgeons of the said pins or catches B, as shown in fig. 1.

The draught strain upon the pins or catches B is sustained by the sliding bars C, which pass in through the side of the bumper-head and cross the slots in which the said pins or catches work, and against which rest shoulders formed upon the front and rear edges of the said pins or catches B, the front and rear edges of the pins or catches B being so formed that the said pins or catches may be raised freely by the entering link D, to couple the cars, the outer ends of the rear slides C being pivoted to facilitate this.

The outer ends of the forward slides C are attached and the outer ends of the rear slides C are pivoted to the ends of the two bars E, the middle parts of which are connected, by the connecting-bar, F, through a hole, in the centre of which passes a guide-rod or pin, G, rigidly attached to the bumper-head, and provided with a spring catch, H, which, by pressing against the bar F, holds the slides C in place, and prevents them from working out while the cars are coupled.

To uncouple the cars, the slides C are drawn out, which allows the link D to be withdrawn by drawing the pin or catch B forward.

Upon the rear edges of the lower part of the pins or catches B is formed a notch, to hold the link D until it has entered the other bumper-head.

Having thus described my invention,

I claim as new, and desire to secure by Letters Patent—

1. The detachable incline a , in combination with the bumper-head A, substantially as herein shown and described, and for the purpose set forth.

2. The combination of the coupling-pins or catches B and slides C with each other, and with the bumper-head A, substantially as herein shown and described, and for the purpose set forth.

3. The combination of the coupling-pins or catches B, slides C, bars E, connecting-bar F, and guide-bar or pin G, provided with a spring catch, H, with each other, and with the bumper-head A, substantially as herein shown and described, and for the purpose set forth.

MATTHEW QUINN.
